DESIGN FOR A TEETHING RING OR SIMILAR ARTICLE

Daniel Kasen, Newark, N. J.

Application August 26, 1944, Serial No. 115,040

Term of patent 3½ years

(Cl. D83—1)

To all whom it may concern:

Be it known that I, Daniel Kasen, a citizen of the United States of America, residing in Newark, county of Essex, and State of New Jersey, have invented a new, original, and ornamental Design for a Teething Ring or Similar Article, of which the following is a specification, reference being had to the accompanying drawing, forming part thereof, wherein,

Figure 1 is a front elevational view of a teething ring or similar article showing my new design.

Figure 2 is a side elevational view of the teething ring or similar article shown in Figure 1.

I claim:

The ornamental design for a teething ring or similar article, substantially as shown.

DANIEL KASEN.
